UNITED STATES PATENT OFFICE

144,790

DESIGN FOR A BATHROOM UNIT

Donald T. Houpt, Seattle, Wash., assignor to
Boeing Aircraft Company, Seattle, Wash., a cor-
poration of Washington

Application June 18, 1945, Serial No. 120,185

Term of patent 14 years

(Cl. D4—4)

To all whom it may concern:

Be it known that I, Donald T. Houpt, a citizen
of the United States, residing at Seattle, in the
county of King and the State of Washington,
have invented a new, original, and ornamental
Design for a Bathroom Unit, of which the fol-
lowing is a specification, reference being had to
the accompanying drawings, forming part thereof.

Figure 1 is a front elevational view of my bath-
room unit showing my new design.

Figure 2 is a plan view of the unit.
Figure 3 is an end elevational view of the unit.
Figure 4 is a perspective view of the unit.
I claim:

The ornamental design for a bathroom unit,
as shown.

DONALD T. HOUPT.
